FOREIGN PATENT DOCUMENTS

EP 1070894 A2 1/2001

Primary Examiner — Cynthia Underwood

(74) *Attorney, Agent, or Firm* — Dinsmore & Shohl LLP

(57) **CLAIM**

The ornamental design for a hook, as shown and described.

DESCRIPTION

FIG. 1 is a perspective view including a front, top and one side of the hook;

FIG. 2 is a planar view of the front of the hook of FIG. 1; FIG. 3 is a planar view of the rear of the hook of FIG. 1; FIG. 4 is a planar view of the one side of the hook of FIG. 1;

FIG. 5 is a planar view of the other side of the hook of FIG. 1;

FIG. 6 is a planar view of the top of the hook of FIG. 1; FIG. 7 is a planar view of the bottom of the hook of FIG. 1; and,

FIG. 8 is a perspective view including a rear, top and the other side of the hook of FIG. 1.

The broken lines show pins for mounting one portion of the hook to another portion of the hook and form no part of the claimed design.

1 Claim, 5 Drawing Sheets
